CLAIM

The ornamental design for a liquid beverage container as shown and described.

DESCRIPTION

FIG. 1 is a front perspective view of a liquid beverage container;

FIG. 2 is a front view of the liquid beverage container of FIG. 1;

FIG. 3 is a rear view of the liquid beverage container of FIG. 1;

FIG. 4 is a left side view of the liquid beverage container of FIG. 1;

FIG. 5 is a right side view of the liquid beverage container of FIG. 1; and,

FIG. 6 is a top plan view of the liquid beverage container of FIG. 1.

The broken lines shown illustrate portions of the liquid beverage container and form no part of the claimed design.

1 Claim, 6 Drawing Sheets
